COMPOSITE WOOL AND LEATHER SOCK

Calvin Bean, Sykesville, Pa.

Application September 15, 1949, Serial No. 115,820

1 Claim. (Cl. 2-241)

1

This invention relates to new and useful improvements in socks for hunting or other sports wear, and it is among the objects thereof to provide a composite sock structure consisting of yarn and leather, in which the leather constitutes a cushion for the heel bone and a support for the foot tendons.

It is a further object of the invention to provide a composite sock in which the heel portion of leather is attached to the sock by sewn stitches and constitutes a reinforcing to prevent chafing on the heel of the wearer and eliminates wear of the yarn in the heel portion.

The invention will become more apparent from a consideration of the accompanying drawing, constituting a part hereof, in which like reference characters designate like parts, and in which:

Fig. 1 is a side elevational view of an improved sports sock embodying the principles of this invention;

Fig. 2 a side elevational view of a leather heel for socks; and

Fig. 3 a cross-sectional view taken through the heel along the line 3-3, Fig. 2.

In the drawing numeral 1 designates a knitted sock of a medium or heavy grade of yarn for sports wear, particularly for use by hunters, having a reinforced leather heel portion 2 which is secured to the sock 1 by stitching as shown at 3. The leather heel is cut out to conform to the shape of the foot and consists of a top and bottom portion 2 and 4, respectively, which are stitched by folding over and sewing as shown at 5, Fig. 3. By constructing the heel of two pieces it can be shaped to the foot without molding by cutting the upper portion along the curvature of the heel and ankle bone, and by making the lower portion separately and stitching along the seam 5 as shown, the lower portion of the heel can be shaped to suit the foot so that the heel of the wearer will be supported on both sides and the seams will not interfere with foot comfort. The attaching threads 3, by which the leather heel is attached to the sock, may be of any suitable material that withstands abrasion, such as blended yarn of wool, cotton, rayon, or any proper attaching thread.

A soft leather that is pliable is best suited and preferably one that has been treated to be impervious to moisture so that it will not harden when exposed to perspiration.

It is evident from the foregoing description of the invention that a leather reinforced heel for knitted socks shaped to the contour of the

2

foot will provide foot support and will eliminate chafing on the heel which results when knitted socks are worn thin on the heel, which is the place of greatest wear. The leather heel also supports the tendon of the foot which causes severe fatigue in long walking as in hunting, and more than doubles the life of a sock without substantially increasing the cost.

Although one embodiment of the invention has been herein illustrated and described, it will be evident to those skilled in the art that various modifications may be made in the details of construction without departing from the principles herein set forth.

15 I claim:

In a composite sock, a full knit sock and a soft leather protective element, said soft leather protective element comprising an upper portion cut and shaped to snugly embrace the heel portion to the rear of the angle portion of said full knit sock and a lower portion cut and shaped to snugly embrace the bottom portion of said sock and to form a cooperating part with said upper portion, said upper and lower portions being disposed with respect to each other and said sock so that the upper portion snugly embraces the heel portion to the rear of the ankle portion of the sock, and the lower portion the rear bottom portion thereof, a row of stitching with abrasive 20 resistant yarn disposed along the free edges of the upper and lower leather protective portions remote from the rear of the sock strongly securing said portions to said sock, and a row of stitching with finer yarn between the upper and lower portions securing them to each other to 25 form a seam that will not interfere with foot comfort whereby a form-fitting leather protective unit is provided for the heel portion to the rear of the ankle and rear bottom foot portion of said 30 sock.
